SPRAYING DEVICE

Rudolph Bernhardt, Chicago, Ill.

Application February 20, 1939, Serial No. 257,291

3 Claims. (Cl. 299—97)

This invention relates to spraying devices such as commonly used for manual spraying, as for spraying clothes for ironing or other uses.

The objects of the invention are to improve and 5 simplify the construction and operation of devices of this kind whereby they may be made at a low cost and will be effective and convenient in operation; to provide a manually operable sprayer which may be held and operated with one hand, 10 having a handle formed in a desirable shape for supporting the spray pump and container and operating the same; to provide a guide for the reciprocating nozzle of a sprayer of the kind indicated; and to provide such other advantages 15 and novel features as will be described more fully hereinafter.

In the accompanying drawing illustrating this invention,

Figure 1 is a side view of the supporting and operating portion of the sprayer embodying this invention;

Figure 2 is a front view of the same;

Figure 3 is a plan view; and

Figure 4 is a vertical sectional view.

As shown in the drawing, the cap 5 is one 25 adapted to be applied to a container, preferably being screwed thereon in the usual manner. This cap has a center sleeve 6 forming a bearing for the reciprocable hollow piston rod or discharge 30 tube 7. The piston rod coacts with a piston 8 which is supported on the bottom of the container and the piston is raised by means of a spring (not shown) in the manner common to such devices. The piston rod is bent to provide a downwardly 35 and forwardly curved discharge portion 9 having a discharge nozzle 10. The pump is operated by means of a thumb piece 11 on the rod 7. The handle 12 is preferably formed of a single strip of sheet metal and has a straight horizontal portion 13 which engages with the top of the cap and which may be secured thereto in any desired manner. However for convenience in construction the tube 6 is used for fastening these parts together. A bead 14 engages with the inner portion 40 of the cap and the outer end of the tube is riveted over as shown in 15 to engage with the handle which is thereby held rotatably on the cap.

One portion of the handle extends upwardly and then back over the straight portion 13 in a 50 generally parallel direction to form a hand-hold 16. This portion is curved transversely to form a comfortable grip and has a downwardly extending protuberance or embossment 17 with a hole 18 through which the hollow piston rod 7 extends. The end of the portion 16 is bent down-

wardly as shown at 19 to engage with the upwardly extending portion 20 and is spot-welded or otherwise secured thereto. This forms a generally rectangular loop having one end of the grip portion shaped to receive the first finger of 5 the operator and the other end of the loop shaped to receive the remaining fingers. The projection 17 tends to keep the first and second fingers separated so that they will not interfere with the operation of the piston rod. When the handle 10 is grasped by the fingers in the manner indicated the thumb will readily engage with the thumb piece 11 for operating the pump.

Heretofore with some of the commercial forms of devices of this kind the piston rod has been 15 free to turn with respect to the handle so that some care was necessary to properly position the spray nozzle to direct the spray on the work and also to hold it in this position. In order to overcome such objections I provide a guide for holding the discharge nozzle in relatively fixed position with respect to the handle, or so that it will 20 not rotate. For this purpose a branch 21 of the handle strip extends upwardly and forwardly as shown and is provided with a slot 22 through 25 which the discharge portion 9 extends, thus forming a guide or keeper for the discharge nozzle.

The operation of the device will be obvious to those familiar with such sprayers.

What I claim and desire to secure by Letters 30 Patent is:

1. In a spraying device, the combination of a cap, a handle engaging with said cap, a tubular bearing extending through the cap and handle and having annular projections to hold said parts 35 together, a pump having a reciprocable discharge pipe extending through said bearing, said handle being of generally rectangular loop form, the upper portion of the same being curved to provide a hand-hold and having an opening there- 40 through for the discharge pipe and having a projection around the pipe to prevent the fingers from engaging therewith, said pipe having a lateral discharge portion and a keeper projecting upwardly from the handle and engaging with 45 said portion to prevent the rotation of the pipe with respect to the handle.

2. In a spraying device, the combination of a spray pump having a reciprocable discharge pipe with a discharge portion extending laterally a 50 substantial distance from the axis of the pipe, a thumb piece on the pipe for reciprocating the same, a cap having a bearing therein for said pipe, a handle engaging with said cap, means for securing the handle to the cap, said handle ex- 55

- tending both ways from the pipe and having the upper portion shaped to receive one finger on one side of the pipe and the others on the opposite side of the pipe with the thumb in position 5 to operate the pump, and a projection on the handle extending upwardly and having a slot through which the discharge portion of the pipe extends and providing a keeper therefor to prevent rotation of the pipe.
- 10 3. In a spraying device, the combination of a receptacle having a cap, a handle secured to said cap, a pump having a re-

ciprocable discharge pipe extending through said bearing, said handle being of loop form to provide a convenient hand-hold for operating the device and having a hole therethrough for the discharge pipe, said pipe having a lateral discharge portion, and a keeper projecting upwardly from the handle at a distance from the pipe and engaging with said lateral discharge portion to prevent the rotation of the pipe with respect to the handle. 5

RUDOLPH BERNHARDT.
